UNITED STATES PATENT OFFICE.

WILMAR F. LENT, OF MILWAUKEE, WISCONSIN, ASSIGNOR TO THE CUTLER-HAMMER MFG. CO., OF MILWAUKEE, WISCONSIN, A CORPORATION OF WISCONSIN.

MOTOR-CONTROLLER.

1,311,567.

Specification of Letters Patent. Patented July 29, 1919.

Application filed April 8, 1915. Serial No. 19,885.

To all whom it may concern:

Be it known that I, WILMAR F. LENT, a citizen of the United States, residing at Milwaukee, in the county of Milwaukee and 5 State of Wisconsin, have invented new and useful Improvements in Motor-Controllers, of which the following is a full, clear, concise, and exact description, reference being had to the accompanying drawing, forming 10 a part of this specification.

This invention relates to motor controllers.

One of the objects of the invention is to provide an improved controller having a series wound accelerating switch with means 15 to control said switch at will for positive and negative speed regulation.

A further object is to provide a controller having series wound accelerating switches and in conjunction therewith means for effecting step by step speed regulation thereby 20 for both acceleration and deceleration.

Other objects and advantages will appear hereinafter in connection with the description of the accompanying drawing which diagrammatically illustrates one embodiment 25 of the invention.

Referring more specifically to the drawing, there is shown a motor M having an armature A and a series field winding F adapted for connection across supply lines L and L'. A main switch 1, having a shunt operating winding, is provided to control the continuity of the motor circuit and a plurality of electro-responsive accelerating 30 switches 2, 3, 4 and 5 are provided to control armature resistances r^2 , r^3 , r^4 and r^5 respectively. The accelerating switches are of a well known type, each being provided with a series operating winding 6 for effecting operation of a pivoted contact arm 7 and with a series lock out winding 8 for holding said arm against circuit closing movement under abnormal current conditions, all in a well understood manner. The connections of the 40 series wound switches are such that, upon closure of the motor circuit, the same tend to respond progressively and thereby effect sequential exclusion of the armature resistance sections r^2 to r^5 . The switches 3 and 5 are 45 also provided with shunt holding coils 9 adapted to maintain said switches closed after operation thereof by the series operating coils but independently of the latter. The accelerating switches are further each 50 provided with a shunt lock out winding 10

adapted to act cumulatively with the series lock out winding thereof for electromagnetically governing at will the closure of said switches, as will be set forth hereinafter.

A master controller 11 is provided to control the circuits of the shunt operating winding 12 of main switch 1, the several shunt lock out windings 10 and the two shunt holding windings 9 of the accelerating switches. This controller is shown schematically as 60 comprising stationary contacts 13 to 20 and a rotatable drum having coöperating contact segments 13' to 20' respectively. The movable element of the controller is rotatable from off position through five operative positions a , b , c , d and e to establish circuit connections as hereinafter traced.

First assuming the controller to be moved directly to position e , main switch 1 responds to complete the motor circuit with 75 all of the armature resistance included. During this movement of the controller, the shunt lock out coils 10 of the accelerating switches are progressively energized but immediately deenergized whereby they have 80 no effect on the operation of the accelerating switches. Furthermore, the shunt holding windings 9 of the switches 3 and 5 are also energized at positions b and d of the controller so that after closure of said 85 switches by the series operating windings thereof, they are maintained closed independently of said series windings.

Upon closure of the main switch 1 the motor circuit may be traced from line L by 90 conductor 21 through the motor field F and armature A by conductor 22, through resistance r^4 by conductor 23, through resistance r^2 by conductor 24 through the series lock out winding 8 of switch 2 by conductors 25 and 26 through the series operating winding 6 of said switch, by conductor 27 through the resistance r^3 by conductor 28 through resistance r^5 , by conductor 29 across main switch 1 and by conductor 30 to line 100 L'. As both the series operating and lock out windings of switch 2 are thus included in circuit, said switch will respond under normal current conditions, and in closing the same cuts out resistance section r^2 and 105 its own series lock out winding 8 by a circuit which includes the series operating and lock out windings of the succeeding accelerating switch 3. This last mentioned circuit is traceable from conductor 23 by conductor 110

31 through both the series and lock out operating windings of said switch 3, by conductor 32 across switch 2 to conductor 26 and thence to line L' as already traced. 5 Switch 3 thereupon responds to complete circuit from the left side of the resistance r^4 by conductor 33 through the series lock out winding 8 of switch 4, by conductors 34 and 35 through the series operating winding 10 of said switch, by conductor 36 across switch 3, by conductor 37 to the right hand side of resistance r^5 and thence to line L'. Resistance section r^3 is thus short circuited as well as the series lock out winding 8 of 15 switch 3 and the operating windings of both switches 2 and 3. Switch 2 thereupon opens, but switch 3 is maintained closed by the shunt holding winding 9 thereof as above mentioned and as will appear more 20 specifically hereinafter. Switches 4 and 5 then respond sequentially in an identical manner to the prior sequential response of the group of switches 2, 3 and serve to respectively short circuit resistance r^4 with 25 the lock out winding 8 of switch 4, and resistance r^5 with both the series restraining and operating windings of switch 5 and the series operating winding of switch 4. The latter switch thereupon opens, but switch 30 5 is maintained closed by the shunt holding coil 9 thereof. The circuit completed by said switch 5 may be traced from the right side of the armature by conductor 38 across said switch, and by conductor 39 to conductor 29 and thence as traced. The operation described thus provides for automatic acceleration of the motor with concomitant protection against overloads.

As above indicated, movement of the controller 11 to positions *a*, *b*, *c* and *d* establishes connections for the shunt lock out windings 10 of the respective accelerating switches. Accordingly, by stopping the controller at any one of said positions the 40 energization of the respective shunt lock out coil may be maintained at will with an attendant functioning thereof to magnetically restrain response of the associated accelerating switch. Thus the voluntary control of the resistance sections r^2 , r^3 , r^4 and r^5 is attained to thereby utilize the same for step by step speed regulation in accelerating. Likewise, as indicated above, the shunt holding winding 9 of switch 3 is energized 45 in positions *b*, *c*, *d* and *e* of the controller, and the holding winding 9 of switch 5 is energized in positions *d* and *e* thereof. Accordingly, movement of the controller in the reverse direction from position *d* 50 rupts the circuit of the shunt holding winding 9 of switch 5 so that said switch opens and thereby includes in the motor circuit the two resistance sections r^5 and r^4 . Continued movement of the controller from position *b* to position *a* similarly interrupts

the circuit of the shunt holding winding of switch 3 which thereupon opens to include the remaining sections r^2 and r^3 of the armature resistance. This reverse operation of the controller thus provides for a limited step by step speed regulation in decelerating. It will be observed also that from either position *c* or *a* the controller is operable forwardly to re-accelerate without an intervening interruption of the motor circuit. 70 75

While the control circuits are readily discernible the same may be briefly traced as follows: Circuit of the shunt winding of switch 1 extends from line L by conductor 40, through the winding, by conductor 41 across contacts 14, 14', 13' and 13 of the controller and by conductor 42 to line L'. The shunt lock out windings 10 of the accelerating switches are all connected by conductors 43 and 21 to line L and on the other side lead through conductors 44, 45, 46 and 47 to the stationary contacts 15, 16, 18 and 19 respectively of the controller and through the corresponding movable contacts of the latter to contact 13 and by conductor 42 to the line L'. The shunt holding windings 9 of the accelerating switches 3 and 5 are likewise connected by conductors 48 and 21 to line L and on the other side by conductors 49 and 50 to stationary contacts 17, 20 of the controller and through the corresponding contact segments of the latter to line L' as already traced. The controller contacts are arranged as indicated to complete the following circuits in the respective controller positions: In position *a*, to energize the operating winding of main switch 1 and the shunt lock out winding of the first accelerating switch 2; 105 in position *b*, to interrupt the circuit of said lock out winding of switch 2 and energize the shunt lock out winding 10 and shunt holding winding 9 of switch 3; in position *c*, to interrupt the circuit of said lock out winding of switch 3 while continuing the energization of the shunt holding winding 9 of said switch and completing circuit to the shunt lock out winding of switch 4; in position *d*, to interrupt the circuit of said 110 lock out winding of switch 4 and to energize the shunt lock out winding 10 and shunt holding winding 9 of switch 5 while continuing the energization of the shunt holding winding 9 of switch 3; in position *e*, to interrupt the circuit of said lock out winding of switch 5 while still continuing the energization of the shunt holding windings 9 of both switches 3 and 5. 115 120

While the foregoing description has been 125 confined to a non-reversible motor having a series field winding, it is to be understood that the controller is susceptible of application as well in various other relations with motors having other characteristics. Fur- 130

thermore, the controller may be embodied in various other forms. For example, the controller might be employed for effecting speed regulation in acceleration only, in which case the shunt holding windings 9 of the accelerating switches 3 and 5 might be eliminated and the connections of said switches arranged similarly to the switches 2 and 4.

10 What I claim as new and desire to secure by Letters Patent is:

1. In a motor controller, the combination with a series wound accelerating switch acting upon response thereof to shunt its operating winding, of means controllable at will and independently of said operating winding to restrain said switch against response and to hold said switch after response thereof.

20 2. In a motor controller, the combination with a series wound accelerating switch acting upon response thereof to shunt its operating winding, of windings to restrain said switch against response and to hold

25 the same after response thereof and means to control said restraining and holding windings at will for acceleration and deceleration of the controlled motor.

3. In a motor controller, the combination with an accelerating switch having series operating and lockout windings, said switch upon response thereof acting to shunt its operating winding, of means independent of said windings to render said switch controllable at will for acceleration and deceleration of the controlled motor.

4. In a motor controller, in combination, means adapted to control the continuity of circuit of the controlled motor, a plurality of series wound accelerating switches, certain of the same acting upon response thereof to shunt their respective operating windings and means to hold a plurality of switches in closed position and to subject 45 the same to release at will for deceleration of the motor to different degrees.

5. In a motor controller, in combination, means adapted to control the continuity of circuit of the controlled motor, a plurality of series wound accelerating switches and means subjecting said switches to control at will for increasing and decreasing the motor speed step by step, the series windings of said switches being independent of said 55 means.

6. In a motor controller, in combination, electromagnetic means adapted to control the continuity of circuit of the motor, a plurality of series wound accelerating switches,

certain of said accelerating switches also having shunt windings for restraining them against operation and holding the same after operation and a common controller for said means and said shunt windings to provide for acceleration and deceleration of the controlled motor at will.

7. In a motor controller, in combination, means adapted to control the continuity of circuit of the controlled motor, a plurality of series wound accelerating switches and electromagnetic means subjecting said switches to control at will for step by step acceleration and deceleration of the motor, the series windings of said switches being independent of said electromagnetic means.

8. In a motor controller, in combination, means adapted to control the continuity of circuit of the motor, an electro-responsive accelerating switch having a series operating and a series lock out winding, and means including a shunt lock out winding to coöperate with said series lock out winding for controlling said switch.

9. In a motor controller, in combination, means adapted to control the continuity of circuit of the motor, an accelerating switch having series operating and lock windings, a shunt lock out winding associated with said series lock out winding to control response of said switch, and a shunt holding winding to maintain said switch closed independently of said series operating winding.

10. In a motor controller, in combination, means adapted to control the continuity of circuit of the motor, a plurality of groups of accelerating switches having series operating windings, each of said groups including a plurality of said switches and one switch of each group upon closure short circuiting the series operating windings of the switches of its respective group, and means to control said one of said switches at will while the motor circuit is completed.

11. In a motor controller, in combination, means adapted to control the continuity of circuit of the motor, a plurality of groups of accelerating switches having series operating windings, each of said groups including a plurality of said switches and one switch of each group upon closure short circuiting the series operating windings of the switches of its respective group, and means to control each of said switches at will in accelerating and to control said one switch of each group at will in decelerating.

In witness whereof, I have hereunto subscribed my name.

WILMAR F. LENT.
